Primary Examiner — Catherine R Oliver-Garcia*(74) Attorney, Agent, or Firm* — Law Office of Scott C Harris, Inc(57) **CLAIM**

The ornamental design for a bee swarm trap, as shown and described.

DESCRIPTION

FIG. 1 is a front perspective view of the bee swarm trap;
FIG. 2 is a front view of the bee swarm trap;
FIG. 3 is a rear view of the bee swarm trap;
FIG. 4 is a side elevation view of the bee swarm trap;
FIG. 5 is an opposite side elevation view of the bee swarm trap;
FIG. 6 is a top view of the bee swarm trap; and,
FIG. 7 is a bottom view of the bee swarm trap.
The broken line showing of portions of the bee swarm trap is included for the purpose of illustrating only and forms no part of the claimed design.
